CORROSION PREVENTATIVE

Herbert Spencer Polin, Port Washington, N. Y.,
assignor to Polin, Inc., New York, N. Y., a corporation of Delaware

Application December 12, 1933, Serial No. 701,976

1 Claim. (Cl. 204—25)

The present invention relates to method and apparatus for preventing corrosion of metallic surfaces in contact with gaseous or liquid fluids.

In accordance with accepted theory a non-homogeneous metal in contact with an electrolytic or ionizable solution constitutes a multiplicity of simple short circuited voltaic cells, wherein electronic currents flow within the metal from particles of the more reactive to particles of the nobler metal. Within the solution the converse is true, that is, the flow of electronic current is from the nobler to the more reactive metal. The consequence is that the more reactive metal passes into solution with liberation of hydrogen gas at the surfaces of the nobler metallic particles.

It has heretofore been proposed to overcome corrosion thus produced by suspending in the solution metallic bars, webs, or the like, between which and the metallic surface to be protected, a source of direct voltage is connected with its negative electrode joined to the protected metal. The magnitude of the resulting electronic current flowing within the solution from the protected metal to the suspended members is then adjusted manually, according to the known practices, to equal or exceed the corroding electronic current, due to voltaic cell action, tending to flow into the more reactive portions of the protected surfaces, in consequence of which the more reactive metal is prevented from passing into solution and the protected surface maintained intact.

The difficulty with known methods wherein the compensating current flow is manually adjusted to offset the effect of the corroding current, resides in the fact that the latter vary in magnitude within wide limits and more or less continuously due, for example, to temperature changes, fluctuations in strength of the electrolytic solution, etc. If therefore the compensating current is manually adjusted to equal the corroding currents for a given instantaneous set of conditions, subsequent unbalances of one polarity will permit corrosion of the protected surface to proceed, while unbalances of the opposite polarity will entail consumption of the suspended bars or web members. Thus after a period both the protected surface as well as the suspended members will be found badly corroded.

If, on the other hand, the compensating current is established of such large magnitude as to more than counterbalance for all conditions the flow of corroding current, the suspended members will be completely consumed within

such short intervals as to render this expedient impracticable.

The present invention eliminates the defects noted by making adjustment of the compensating current electrically automatic and such that the compensating current can be caused to just balance the corroding current for all fortuitous variations of the latter; or in the alternative the compensating current can be made to vary automatically in response to variations of the corroding current, but in such manner as always to exceed the corroding current by a substantially constant amount. Thus the present invention will assure complete and continuous protection of the metal to be preserved, while causing no consumption of the suspended members, or a consumption thereof which can be made as gradual as desired. It will be appreciated that adjustment of the compensating current to more than counter-balance the corroding current constitutes, in a sense, a factor of safety assuring the elimination of all corroding effects in the protected surface.

Although not limited thereto, the invention is particularly applicable to the condensing apparatus used on lighter-than-air craft, in which the moisture content of the exhaust gases from the motors, is condensed so as to prevent, as far as possible, the lightening of the ship as fuel is burned. Since in airships any excess weight is undesirable, the condensing pipes are made as thin as possible, and it has been found that these pipes are very rapidly corroded by the fuel exhaust gases condensed, necessitating frequent replacement of the pipes.

This corrosion is due partly to the presence of carbon monoxide and carbon dioxide in the exhaust gases, which in solution form acids, and, being in contact with the metallic condenser tubes, permit electrolytic action to take place of the character above described, which is intensified at the high temperatures of operation. The corrosion is in this instance also due to the fact that some or all of the molecules composing the exhaust gases, are electrically charged, whereby in the condensing process small electric currents are set up which additionally corrode the walls of the tube.

The present invention which compensates and hence eliminates both types of corrosion, employs for maintaining the compensation electrically automatic, a space discharge device, such as an electronic tube having an anode, a cathode and grid electrodes. The cathode system of the tube is effectively grounded to the protected sur-

face. Insulatedly suspended in the electrolytic solution or in the exhaust gases are a pair of conductive elements or screens, which may comprise concentric cylindrical meshes. The suspended elements are joined respectively to resistors interposed in the grid and anode circuits of the tube. The connections and electrical magnitudes are such that changes in conductivity or voltage developed within the fluid medium apply to the grid of the tube instantaneous potentials of proper magnitude and polarity to provide in its anode circuit the desired instantaneous value of compensation.

In the drawings: Fig. 1 shows diagrammatically a form of the invention adapted to eliminate corrosion where the corroding currents are of constant polarity, either plus or minus, although susceptible to fluctuations in magnitude.

Fig. 2 shows an adaptation of the Fig. 1 arrangement to an extensive conduit system to be protected.

Fig. 3 shows a modification adapted automatically to compensate for corrosion currents varying fortuitously in both magnitude and polarity.

Fig. 4 shows an arrangement employing a gaseous or glow discharge tube for supplying relatively large compensating current where required.

Referring to Fig. 1, there is shown in longitudinal section a fluid conduit or container C, containing either a gaseous medium interspersed by charged particles, such as the exhaust gases of motors, or an electrolytic medium, or both. Insulatedly mounted within the container, as by porcelain or ceramic supports 2, are a pair of conductive elements or screens S and D, here shown as longitudinally spaced but which may be concentric cylinders. Screen D is connected by means of a conductor 5 through an insulating plug 6, to the grid G of an electronic tube V.

The cathode K, of the tube is energized from battery B₁, through a resistor R, variably tapped through leak resistor L to the grid G of tube V, for biasing the grid as desired. The anode circuit of the tube, energized by battery B₂, contains a potentiometer P, the midpoint M of which is tapped by means of conductor 7 through an insulating plug 8 in the container, to screen S therein. The container C to be protected against corrosion, is variably tapped at T to potentiometer P by means of conductor 10 containing an ammeter 11.

Assuming container C to be filled with an electrolytic solution E, batteries B₁ and B₂ will establish in grid resistor L, with the system as arranged in the drawings, an electronic current i_1 flowing in the solution from screen D to the container C returning over conductor 5. This current will be so small, due to the large value of the grid resistor L, as to produce no appreciable effect on meter 11. Concurrently the space current of tube V will, in traversing the potentiometer P, establish a potential drop between points T and M thereof, producing an electronic current i_2 flowing from container C to screen S in the solution.

It will be observed that current i_2 is in the right direction to compensate or counterbalance the electronic current flowing into the more active metal portions of container C in consequence of the voltaic cell action described. For a given set of conditions, conductivity of the solution, etc., current i_2 can be so adjusted by variation of potentiometer tap T and by observation on meter 11, as to prevent corrosion of con-

tainer C so long as the initial conditions remain unaltered.

Assume, however, that by some fortuitous circumstance the conductivity of solution E should increase, as by increase of temperature, increase of concentration, etc. The resulting increase in corrosive voltaic cell action established between the more and less active portions of the non-homogeneous container C, immediately necessitates an increase in the compensatory current i_2 , which is the result automatically produced by the vacuum tube system as follows:

The increase in conductivity of solution E, decreases the total resistance in the path traversed by the grid current i_1 , in consequence of which current i_1 increases thereby increasing the voltage drop across grid resistor L, and thus increasing in a positive sense the biasing potential applied to control grid G. This produces an increase of space or anode current in tube V, which in traversing the potentiometer P, increases the voltage between points T and M thereof, and hence increases the magnitude of current i_2 from container C to screen S, which is the result desired.

If on the other hand the conductivity of solution E should decrease, the corroding currents would decrease and a smaller compensating current i_2 would suffice. The system of the drawing automatically provides for this in a manner which is just the converse of that above described for an increase in conductivity of the solution. As the conductivity of the solution decreases, the grid current i_1 likewise decreases, thereby decreasing in a positive sense or increasing in a negative sense the biasing potential applied to grid G. This decreases the space current of tube V, and hence the magnitude of the compensating current i_2 , which again is the result desired.

Therefore, irrespective of whether the conductivity of solution E increases or decreases from a given condition, the compensating current i_2 will automatically vary in the same direction along with it, that is current i_2 always varies automatically in magnitude in the same direction as do the forces tending to produce corrosion.

Now from a series of preliminary tests based on the character of electrolyte or charged gaseous fluid normally present in container C, the metallic structure of the container as well as screens S and D, etc., the optimum value of current i_2 for minimizing corrosion of all metallic surfaces, can be ascertained for various conductivities of the fluid. With this information preliminarily available, the system can be so designed as automatically to maintain the current i_2 at its optimum value throughout the range of fluid conductivities encountered in practice. Factors determinative of this design are the resistances of L and potentiometer P, the magnitude of batteries B₁ and B₂, characteristics of tube V, etc. By suitably proportioning these circuit components the current i_2 can not only be made to vary automatically in the right direction but by just the proper amount to effect optimum compensation for each change in conductivity of the fluid.

Where, as in the case of condensation of exhaust gases from motors, charged particles of the gaseous medium tend, in discharging to the grounded pipe 1, to set up a flow of corroding current to or from the pipe, optimum compensation may be effected by so adjusting the compensating current i_2 that the meter deflection is 75

zero, since for this adjustment the compensating current would be equal and opposite to the corroding current. It will be observed in this connection that if found necessary, the polarity 5 of the compensating current i_2 can be reversed in sign as well as adjusted in magnitude by merely shifting the variable tap T to one side or the other of the midtap M.

The invention is not limited to a single tube V 10 for providing the automatically regulated compensating current or voltage. It may be advisable in certain cases to arrange additional tubes in tandem with tube V, in which event the potentiometer P would be interposed in the anode 15 circuit of a subsequent tube, tube V merely serving to continuously detect the requisite electrical characteristic of fluid E, and to control in accordance therewith the voltage applied to a subsequent tube, which in turn would provide the 20 proper compensating voltage or current.

In this connection the employment of a plurality of tubes in tandem provides a means alternative to the mid-tap M of potentiometer P for reversing the polarity of the compensating voltage. Thus the midtap M could conveniently be 25 shifted to the lower terminal of the potentiometer.

In the case of a large ship, complex relationships, electro-potentially, between the various pipes, the hull, the sea water and stray electrical 30 currents leaking from the electrical conduits, may impart to the metallic structure a multiplicity of currents varying in sign, potential and magnitude at any moment. The system herein described provides for the installation of a detecting and distribution panel identified with an electrical network throughout the ship, and with a central power supply located at the distribution panel so introduced into each circuit as to effectively neutralize the many and variable currents 35 flowing at those points located as major potential difference sources. The area of effectiveness of each neutralizing circuit may be determined by the metallurgical bulk of this branch, by the area of the source of potential difference, and by the 40 proximity of the neutralizing system to each source.

Fig. 2 shows the manner of adapting the invention to a continuous conduit system traversed by a fluid medium of corrosive character. The conduit system, which may represent the sea water damage control mains of a battle ship, etc., comprises pipe sections C₁, C₂, C₃, etc. At appropriate intervals, as best determined by tests on the particular system under consideration, are 45 insulatedly positioned in the fluid medium, the screens S₁, S₂, S₃, connected to potentiometers P₁, P₂, P₃, etc., arranged in the anode circuits of tubes V₁, V₂, V₃, etc. in the manner of Fig. 1. Concentric with screens S₁, S₂, S₃, etc., respectively, or appropriately spaced therefrom, are the detector screens D₁, D₂, D₃, etc., joined to the grids of tubes V₁, V₂, V₃ respectively. All of the tubes are energized from the common filament and space current supply sources B₁ and B₂, as shown. In the operation of the system the variable arms of the potentiometers P are individually adjusted to eliminate corrosion in the particular pipe section containing the associated screens S and D.

Referring to Fig. 1, with a given setting of variable tap T, automatic compensation will be effected for corroding currents of but one polarity. An arbitrary reversal of the corroding polarity will necessitate shifting tap T from one side to 75 the other of the midtap M. The system of Fig. 3,

employing a separate detector tube V₁ regulating the oppositely controlled tubes V₂ and V₃, automatically compensates corroding effects varying fortuitously in magnitude and direction.

The detector tube V₁ has its grid G₁ grounded 5 to container C over lead 20, and its cathode connected over lead 21 to a detector screen D positioned in contact with the fluid E of container C. The space current of tube V₁ traverses a potentiometer P₁ variably tapped at T_a and T_b and 10 connected by means of conductors 22 and 23, in opposite polarity between grid and cathode of tubes V₂ and V₃ respectively.

The anode current of tube V₂ traverses a potentiometer P₂, the positive terminal of which is 15 connected to a screen S₁ in contact with the fluid, with the variable tap T₂ grounded to container C. Similarly the anode current of tube V₃ traverses a potentiometer P₃, which, in this case, has its positive terminal grounded to container 20 C and its variable tap T₃ joined to screen S₃ within the container.

In the operation of this system, with no corroding voltage applied between screen D and the detector tube grid, tubes V₂ and V₃ are biased 25 to cutoff by adjustment of the grid taps to resistors R₂ and R₃, respectively. Assume now that the fluid medium establishes a corroding voltage such as to make the screens negative with respect to the container, thereby establishing a corroding 30 electronic current flow from the fluid to the container. In order to compensate for the corroding current thus established, tube V₃, which tends to establish a current flow from conduit C to screen S₁, as indicated by arrow a, should be 35 activated.

That this is the result effected is apparent from the fact that the corroding voltage having the polarity assumed, increases in a positive sense the potential of grid G₁ of the detector tube 40 V₁. This in turn increases the flow of space current in potentiometer P₁, in consequence of which grid G₂ of tube V₂ is increased in a positive sense. Tube V₂ thus becomes increasingly biased below cutoff, thereby establishing a flow of the desired 45 compensating current from container C to screen S₁.

Meantime tube V₃ remains inactive, because the increased current flow in potentiometer P₁, increases in a negative sense the potential applied 50 to grid G₃ of tube V₃. Since, tube V₃ is initially biased to cutoff, the increasingly negative potential of its grid produces no flow of space current.

If the corroding voltage is such as to increase 55 in a negative sense the potential of the detector grid G₁, tube V₂ is maintained inactive, while tube V₃ is rendered increasingly active to establish a flow of compensating current from screen S₃ to conduit P.

The circuit of Fig. 4 is ideally adapted to prevent corrosion in extensive conduit systems, such as the sea water ballast pipe lines of battle ships, wherein the total current required for purposes of compensating the corroding currents, is relatively 65 large, and may be considerably in excess of that which can be conveniently supplied by the space current of an electronic tube. Under such circumstances resort may be had to gaseous or glow discharge tubes, such for example as 70 that known as the Thyratron, for providing the compensating current.

In the circuit of Fig. 4 the corroding potentials are detected thermionically by means of the electronic tube V₁ having its grid G₁ connected, 75

through short circuiting contacts of a switch 25 to the conduit C, and its cathode connected to detector screen D positioned in the fluid medium E within the conduit.

5 If the fluid E comprises an electrically charged gaseous medium, a potential will be established on grid G₁ determined by the polarity and magnitude of the charge existing between screen D and the conduit C. If on the other hand the 10 fluid is an ionized liquid, switch 25 may be operated to connect the battery 26 in the grid circuit, in order to establish a current flow in the resistor L₁, the voltage drop across which will depend upon the conductivity of the electrolyte.

15 In any event the corroding forces thus detected establish, by variation in the space path resistance of tube V₁ automatic regulation of a grid controlled, glow discharge tube V₂, such that a compensating current is caused to flow between 20 screen S and conduit C which varies in conformity with the corroding forces.

25 As is well known, the operation of grid controlled gaseous discharge tubes necessitates periodically interrupting the flow of space current in order to maintain operation of the device under control of its grid. To this end tube V₂ is energized from an alternating current source 27 connected to a transformer 28 having secondary windings 30 and 31, the one for energizing the 30 cathode K₂, and the other for applying an alternating potential between the cathode K₂ and the anode A₂.

35 The magnitude of space current supplied by tube V₂ is regulated under control of tube V₁ by connecting its grid, G₂ through the variable resistance consisting of potentiometer P₁ in shunt to the space path resistance of tube V₁, and thence to cathode K₂ through a secondary winding 39 of transformer 28. An inductance 33 is 40 connected between grid G₂ and anode A₂. With the elements properly proportioned, variation in

the space path resistance of tube V₁ in response to variations in its grid potential, produces a relative shift in phase of alternating current applied between grid and cathode of tube V₂ with respect to that applied between its anode and 5 cathode such as to vary in the manner required for automatic compensation the average space current of tube V₂.

Connected in the anode circuit of tube V₂ is a low pass filter 32 the output of which terminates in a potentiometer P₂ variably tapped at T₂ to screen S, with the positive terminal of potentiometer connected to conduit C.

The rectified pulsating current flowing between anode and cathode of tube V₂ is thus converted by the filter 32 into a non-pulsating direct current traversing potentiometer P₂, thereby providing the requisite flow of compensating current between screen S and conduit C.

I claim:

Means preventing corrosion of a metallic surface subjected to corrosive action of a fluid comprising, a plurality of grid controlled space discharge devices, metallic screens individual thereto insulatedly positioned in said fluid, means responsive to the space current of a first said tube for passing between its associated screen and the metallic surface a compensating current of one polarity, means similarly responsive to the space current of a second said tube for passing between its associated screen and the metallic surface a compensating current of the opposite polarity, means whereby a third tube detects the potential difference between its associated screen and the metallic surface tending to produce corrosion, and means whereby said third tube selectively regulates the flow of space current in said first and second tubes automatically to compensate for corroding currents varying fortuitously in magnitude and polarity.

HERBERT SPENCER POLIN.
